UNITED STATES PATENT OFFICE.

ERIC ELIAS SVENSSON, OF GOTTFENBORG, SWEDEN.

DETENT FOR CALCULATING-MACHINES.

1,334,974.

Specification of Letters Patent. Patented Mar. 30, 1920.

Application filed June 24, 1919. Serial No. 306,469.

To all whom it may concern:

Be it known that I, ERIC ELIAS SVENSSON, a subject of the King of Sweden, residing at Gottenborg, in the county of Gottenborg 5 and Bohus and Kingdom of Sweden, have invented new and useful Improvements in Detents for Calculating-Machines, of which the following is a specification.

This invention refers to calculating machines of the type set forth in the U. S. 10 patent to Trinks, 1149872, wherein adjustable pins or a variable number of pins on the counting disks operate the toothed gears in the indicating mechanism. Particularly 15 this invention refers to the detents in the said type of calculating machines, which detents have for object to check the gears of the indicating mechanism when these gears are not operated upon by the counting disks. 20 More particularly this invention has reference to means for automatically releasing the coaction between the detents and the indicating gears when the adjustable pins of the counting disks pass by and operate the 25 said indicating gears.

The object of this invention is an automatically operative device to release the said coöperation between the detents and the indicating gears for the purpose to avoid the 30 noise otherwise effected by the detents when sliding over the teeth of the gears in the indicating mechanism as the last mentioned gears are caused to rotate by the influence of the operative adjustable pins of the counting disks. 35

In the accompanying drawing an embodiment of the invention is shown, whereby:

Figure 1 shows a cross sectional view of a 40 portion of a calculating machine with the present detent in a certain operative position,

Fig. 2 a similar view with the detent in another operative position,

Fig. 3 the same parts with the detent in a third operative position and

Fig. 4 a top view of the machine with a part cut away to show the detent.

1 denotes one of the counting disks in a 50 known manner provided with adjustable pins 2, which gear with one of the toothed gear 3 of the indicating mechanism by means of an intermediate pinion 4. The indicating mechanism gear 3 is kept in the proper position by a detent 5, the arm of which is de-

signed as a double-armed lever 6 and oscillating around a pivot 8 in a member 7 projecting laterally from the lever 6. A spiral-spring 9 acts upon the lever 6, at the end with the detent 5 and tends to cause the 60 detent to coöperate with the teeth of the wheels 3. The lever 6 in the opposite end is provided with a pivot 10, upon which oscillates as a double armed lever a member 65 11 with rounded or sloping ends, and positioned close beside the intermediate pinion 4. The adjustable pins 2 of the disk 1 are of such a design and width, that they gear with the teeth of the intermediate pinion 4 at the same time as they actuate the oscillating member 11 as shown in Fig. 4.

The operation of the improved device will be as follows:

When the pins 2 of the counting disk 1 are adjusted in position for a certain calculation and the disk 1 is rotated for instance in the direction of the arrow in Fig. 1, the first pin 2 will meet and act upon the member 11 (Fig. 1) in such a manner, that the said member by the continued rotating of the disk 1 will be tilted a little and slide on the top of the passing pins 2. The pressure thereby exerted on the lever 6 of the detent 5 will cause the same to swing on the pivot 8 into the position, shown in Fig. 2 85 in such a way, that the detent 5 is removed off the path of the teeth of the indicating gear 3 and remains disengaged in this position so long as the teeth of the intermediate pinion 4 are in gear with the pins 2 of 90 the counting disk 1, and accordingly the indicating mechanism gear 3 rotated by means of the intermediate pinion 4. As a consequence there will be no engagement between the detent 5 and the teeth of the 95 gear 3 during the revolving of the last mentioned gear and thus the revolving will be achieved noiselessly. When all the operative pins 2 have passed the teeth of the intermediate pinion 4 the member 11 again 100 gets tilted but in an opposite direction and slips off from the pins 2 (Fig. 3), whereby the detent 5 by the influence of the spring 9 will be thrown back into its locking position in gear with the gear 3.

Having thus fully described my said invention and how it is to be performed what I claim as new and desire to protect by Letters Patent is:

1. In a calculating machine the combina- 110

tion with a counting disk having adjustable pins, intermeshing indicator mechanism gears one of which is engaged at suitable intervals by the pins of the disk so as to be rotated thereby, a detent co-acting with the other gear, and means co-acting with the detent and normally lying against the disk in the path of the pins to cause a disengagement of the detent at the time the pins engage the said gear.

2. In a calculating machine, the combination with a counting disk having adjustable pins, indicating mechanism gears, one of which is engaged at suitable intervals by the pins of the disk during rotation of the latter so as to insure of rotation of the gears, a double armed lever pivotally mounted in proximity to the gears and disk, a detent on one arm of the lever for engaging the other gear, a spring bearing against the arm of the lever carrying the detent for normally holding the detent in yieldable engagement, and means mounted on the other arm of the lever and lying against the disk in the path of the pins so as to be engaged by the pins during rotation of the disk to cause a disengagement of the detent at the

time the pins engage the first mentioned gear.

3. In a calculating machine, in combination, a counting disk having adjustable pins, a rotatably mounted indicator mechanism gear, a rotatably mounted indicator mechanism pinion meshing with the gear and positioned so as to be engaged at suitable intervals by the pins of the disk so that rotation of the latter insures of rotation of the pinion and gear, double armed lever pivotally mounted in proximity to the gear and pinion, a detent carried by one arm of the lever for engagement with the gear, means for yieldingly holding the detent in its engaged position, and an oscillatory member mounted on the other arm of the lever and having its curved engaging face lying against the disk and in the path of movement of the pins so as to be slidably engaged at times by the pins of the disk to cause a swinging of the double armed lever and a disengagement of the detent at the time the pins engage the pinion.

In testimony whereof I have affixed my signature.

ERIC ELIAS SVENSSON.
